R. WINNE,
METHOD OF AND MEANS FOR EFFECTING THE COMBINATION OF GASES,
APPLICATION FILED OCT. 20, 1913.

UNITED STATES PATENT OFFICE.

ROY WINNE, OF SCHENECTADY, NEW YORK, ASSIGNOR TO GENERAL ELECTRIC COMPANY, A CORPORATION OF NEW YORK.

METHOD OF AND MEANS FOR EFFECTING THE COMBINATION OF GASES.

1,166,294.

Specification of Letters Patent. Patented Dec. 28, 1915.

Application filed October 20, 1913. Serial No. 796,128.

To all whom it may concern:

Be it known that I, Roy WINNE, a citizen of the United States, residing at Schenectady, county of Schenectady, State of New York, have invented certain new and useful Improvements in Methods of and Means for Effecting the Combination of Gases, of which the following is a specification.

My present invention relates to an improved method for effecting the combination of two or more gases and more especially to a method for isolating the nitrogen of the air by causing the oxygen to unite with some other gas to form a product which may more easily be separated from the nitrogen, and means for carrying out this method. Numerous methods have been devised heretofore for accomplishing this result but the gas obtained commercially, unless prepared or purified by expensive complicated processes, contains an appreciable amount of oxygen, usually at least five per cent. For certain purposes the presence of as much as five per cent. of oxygen renders the nitrogen absolutely useless. By my method, however, I am able to secure nitrogen containing less than one half of one per cent. of oxygen. This small amount is not enough to seriously depreciate the gas for common commercial use. If it is desired to have nitrogen absolutely free from oxygen the small percentage of oxygen remaining may of course be removed by well known chemical means.

One common method in use for isolating the nitrogen consists in burning out the oxygen of the air by means of a flame of hydrogen or other suitable reducing gas. By this method it is exceedingly difficult to regulate the flame so as to prevent it from going out at times. As a result whenever the flame goes out a certain amount of uncombined gas passes through into the receiver. By another process the air and gas are mixed at the junction of two tubes before heating and the mixture is passed through a furnace heated to a temperature at which the two gases will combine. By my invention however the two gases are heated to a temperature at which combination will take place and then mixed, and as a result I secure a practically perfect combination of the oxygen with the reducing gas, if a sufficient amount of gas is supplied.

While my invention is especially useful in the process described for isolating the

nitrogen of the air it is by no means limited to this particular process but is of great utility in effecting the combination of any two or more gases which will combine with each other when brought into contact at a high temperature.

In its broader aspect my invention comprises the use of a porous diaphragm provided with means for initially bringing it to a temperature at which the gases will combine. The heat of the diaphragm is then communicated to the gases and they are brought into contact with each other at or near the surface of the diaphragm. Preferably one of the gases is brought through the pores of the diaphragm in order to insure that it will be heated to the desired temperature before it can come in contact with the other gas or gases; that is, one gas may be heated by passing through the diaphragm while the other is heated by contact with the heated surface or by the radiation of heat therefrom. In some cases the heat liberated by the combination of the gases will be sufficient to maintain the diaphragm at the required temperature after the reaction has once been started and as long as the gases are continuously supplied in the proper quantities. In case the heat liberated in this way is not sufficient, however, the operation of the initial heat supplying means may be made continuous.

My invention will be best understood by reference to the accompanying drawing in which I have shown one convenient form of apparatus for carrying out my method and in which—

Figure 1 is an elevation partly broken away to show the interior construction of the furnace which I use, and Fig. 2 is a cross section on the line X—X of Fig. 1.

The furnace which I use in carrying out my process comprises an air tight casing 1 through which passes a tube 2 preferably of alundum. This is especially suitable because of the fact that as well as being porous it is highly refractory. Around the central portion of the tube there is wound a heating element 3 consisting of a wire of platinum, tungsten or other refractory metal. The end portions of the tube not covered by the heating element as well as those portions covered by a few of the end turns of the wire are rendered nonporous by glazing 4 or by a coating of nonporous cement. The

connection between the outside of the tube and the casing is made air tight at one end by means of nonporous cement 5, while at the other end a flexible tube 6 is slipped over the projecting portion 7 of the casing and the end of the alundum tube in order to allow for expansion and contraction of the tube. The terminals 8 of the heating element may be brought out through the cement 16 used to make the air tight connections at the ends of the furnace. Air may be led into the furnace through the pipe 9, the end 10 of the tube being closed by a window through which the interior of the tube may be inspected. The space between the tube and the iron casing is filled with some granular non-conducting medium 11 such as coarse sand. A reducing gas, preferably hydrogen, is supplied to this space by means of the 15 pipe 12 connected to the top of the casing.

The sand filling around the tube prevents any danger of explosion of the hydrogen and the reducing atmosphere enables me to use as a heating element metals such as 25 tungsten which would oxidize rapidly if brought to a high heat in the presence of oxygen.

The operation of this device is as follows: The interior of the tube within the heating 30 element is first brought to the desired temperature, preferably 800 to 900 degrees C., when hydrogen is used and hydrogen is admitted through the pipe 12. This penetrates the porous filling within the casing 35 and the porous portion of the tube, entering the tube only in that section which has been raised to a high temperature. It then unites with the oxygen of the air which is allowed to flow in through the pipe 9, forming 40 water vapor. The pressure of the incoming air and hydrogen may be so regulated that enough hydrogen will be supplied to combine with all of the oxygen of the air which is allowed to pass through. The resulting mixture which consists almost entirely of nitrogen, and water vapor passes from the furnace through the outlet 13 and may then be subjected to any of the well known methods for removing any excess 45 hydrogen, or traces of oxygen and the water vapor. For example, the excess hydrogen and water vapor may be removed by a method similar to that described in Roscoe and Schorlemmer's *Treatise on Chemistry*, 50 vol. 1, 3rd edition (1905), pp. 278, 281, in which heated copper oxid is used for producing water vapor by combination with hydrogen. Any remaining traces of oxygen may be removed by the method described at pp. 488-489, of the above-mentioned book in which heated copper is employed for separating oxygen from nitrogen. I find it convenient to combine these 55 two methods. Upon cooling the gaseous mixture the water vapor condenses and the

remaining gas may then be passed through a highly heated tube containing in one end copper oxid, and in the other end copper. If there is any hydrogen it will reduce the copper oxid and form water vapor, and if there is any uncombined oxygen it will combine with the copper and form copper oxid. Any water vapor formed in the tube and any which was not removed before passing the mixture through the tube may then be removed by any of the methods described by Roscoe and Schorlemmer, as for example, by passing the mixture over potash or phosphoric acid. By this method of operation the hydrogen comes through the pores 60 of the tube in the form of a fine jet or spray and both the hydrogen and the air are raised to a uniformly high temperature before coming in contact with each other, thus insuring a perfect mixture and combination 65 of the oxygen of the air with the hydrogen.

While I have described the operation of my device for the purpose of isolating the nitrogen of the air with hydrogen as the reducing gas, it is obvious that other reducing gases may be used for this purpose with similar results and that the same apparatus might equally well be employed for effecting the combination of other gases than those mentioned. It will also be understood 75 that the form of apparatus which I have shown and described is merely illustrative and that a great variety of modifications thereof may be made without departing from the scope of my invention.

What I claim as new and desire to secure by Letters Patent of the United States, is—

1. The method of isolating the nitrogen of the air, which consists in separately heating air and a reducing gas to a high temperature, causing the reducing gas to come into contact with the air after heating in the form of a fine spray such as would be produced by the passage of the gas through a porous body, and then separating the products of the combination from the nitrogen.

2. The method of isolating the nitrogen of the air, which consists in separately heating air and a reducing gas to a high temperature by contact with a heated porous body, bringing the air and reducing gas into contact with each other after they are heated by causing one of them to pass through the porous body and then separating the products of the combination from the nitrogen.

3. The method of isolating the nitrogen of the air, which consists in separately heating air and hydrogen to a high temperature causing the hydrogen to come into contact with the air after being heated in the form of a fine spray such as would be produced by the passage of the hydrogen through a porous body and then separating the products of the combination from the nitrogen.

4. The method of effecting the combina-

tion of two or more gases, which consists in separately heating the gases to a high temperature and causing one of the gases to come into contact with the other gas or gases 5 after being heated in the form of a fine spray such as would be produced by the passage of the gas through a porous body.

5. The method of isolating the nitrogen of the air, which consists in simultaneously and 10 separately heating air and a reducing gas to a temperature at which they will combine causing the reducing gas to come in contact with the air after both are heated in the form of a fine spray such as would be produced by passing through a porous body and 15 then separating the products of the combination from the nitrogen.

6. The method of isolating the nitrogen of the air, which consists in simultaneously and 20 separately heating air and hydrogen by contact with a heated porous body to a temperature at which they will combine, mixing the air with the hydrogen after both are heated by causing one of them to pass 25 through the porous body and then separating the products of the combination from the nitrogen.

7. The method of effecting the combination of two or more gases which consists in 30 heating the gases separately and simultaneously to a temperature at which combination will take place and then causing one of the gases to come into contact with the other gas or gases in the form of a fine spray such 35 as would be produced by the passage of the gas through a porous body.

8. Means for isolating the nitrogen of the air consisting of a porous wall furnace, means for supplying air to the furnace, 40 means for heating the wall of the furnace, means for supplying a reducing gas through the porous wall of the furnace and means for separating the products of the union of the air with the reducing gas.

45 9. Means for isolating the nitrogen of the air comprising a cylindrical casing, a porous tube passing axially through said casing, a heating element surrounding said tube, a connection for passing air into said tube, a connection for supplying a reducing gas to the space within the cylinder surrounding said tube and a connection for carrying away the products of the union of the air with the reducing gas.

55 10. Means for isolating the nitrogen of the air comprising a cylindrical casing, a tube, a portion of the length of which is porous, passing axially through said casing and sealed to the ends of the casing, a heating element surrounding the porous portion of the tube, a filling of granular non-conducting material between the exterior of the tube and the wall of the casing, a connection for supplying air to the tube, a connection for supplying a reducing gas to the

granular filling, and a connection for carrying away the products of the union of the air with the reducing gas.

11. Means for effecting a combination of two or more gases comprising a porous diaphragm, electrical means for initially heating said diaphragm to a temperature at which the gases will combine, means for bringing at least one of the gases to the heated surface of the diaphragm through 70 the pores thereof and means for carrying away the products of the combination of the gases.

12. Means for effecting a combination of two or more gases comprising a porous diaphragm, means for supplying a gas to one side of the diaphragm, means for passing a second gas through the diaphragm from the opposite side, means for initially heating the diaphragm to a temperature at which the 85 two gases will combine and means for carrying away the products of the combination of the gases.

13. Means for isolating the nitrogen of the air comprising a heated porous body, means 90 for simultaneously bringing air and a reducing gas separately into contact with said heated body to heat them to a high temperature, means for causing the reducing gas to pass through the pores in the body to come 95 in contact with the air in the form of a fine spray after being heated and means for separating the products of the combination from the nitrogen.

14. Means for isolating the nitrogen of 100 the air comprising a heated porous body, means for simultaneously bringing air and a reducing gas separately into contact with said heated body to heat them to a high temperature, means for bringing the air and reducing gas into contact with each other after being heated and means for separating the products of the combination from 105 the nitrogen.

15. Means for isolating the nitrogen of 110 the air comprising a heated porous body, means for bringing air and hydrogen separately into contact with said heated body to heat them to a high temperature, means for causing the hydrogen to pass through 115 the pores of the body so as to come into contact with the air in the form of a fine spray after being heated and means for separating the products of the combination from the nitrogen.

16. Means for effecting the combination of two or more gases, comprising a heated porous body, means for bringing said gases separately into contact with said heated body to heat them to high temperature and 125 means for causing one of said gases to pass through the pores of said body to bring it into contact with the other gas or gases in the form of a fine spray after being heated.

17. Means for effecting the combination of 130

- two or more gases comprising a heated porous body, means for separately bringing said gases simultaneously into contact with said heated body to heat them to a temperature at which combination will take place and means for causing one of the gases to pass through the pores of said body to bring it into contact with the other gas or gases in the form of a fine spray after being heated.
18. Means for isolating the nitrogen of the air comprising a heated porous body, means for simultaneously bringing air and a reducing gas separately into contact with said heated body, means for mixing the air with the reducing gas after both are heated and means for separating the products of the combination from the nitrogen.
19. Means for isolating the nitrogen of the air comprising a heated porous body, means for simultaneously bringing air and hydrogen separately into contact with said heated
- body to heat them to a temperature at which they will combine, means for mixing the air with the hydrogen after both are heated and means for separating the products of the combination from the nitrogen.
20. Means for isolating the nitrogen of the air comprising a porous body, means for heating said body, means for bringing air into contact with one surface of said porous body to heat it to a high temperature and means for simultaneously causing a reducing gas to pass through the pores of said body to heat it to a high temperature and cause it to come in contact with the air in the form of a fine spray.

In witness whereof, I have hereunto set my hand this 18th day of October, 1913.

ROY WINNIE.
